UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A BACK FOR BRUSHES OR SIMILAR ARTICLES.

SPECIFICATION forming part of Design No. 29,531, dated October 25, 1898.

Application filed September 26, 1898. Serial No. 691,960. Term of patent 7 years.

To all whom it may concern:

Be it known that I, WILLIAM C. CODMAN, of Providence, in the county of Providence and State of Rhode Island, have invented and 5 produced a new and original Design for the Back of a Brush or Similar Article, of which the following is a specification, reference being had to the accompanying drawings, forming part thereof.

10 Figure 1 is a view of the back of a brush, showing my design. Fig. 2 is a transverse sectional view through the main body of the back on the line A A of Fig. 1.

The leading feature of my design consists 15 in the brush-back, provided with raised floral ornamentation at the lower end of the handle, from which extend a series of long stems, terminating in scrolled ends. The stems are interlaced and extend upwardly on the handle. 20 Similar curved stems, interlaced with scrolls, extend from the handle along each side of the oval back, inclosing a central panel.

In the drawings, B indicates the oval back 25 of the brush, and C the back of the handle; 3, the raised floral ornament at the end of the handle, and 4 4 curved narrow stems, terminating in scrolled ends and connecting with the ornamentations 5 and 6, consisting of inter-

laced curved stems, partly foliated. From the contracted neck of the handle extend 30 along each side of the oval back the long curved stems interlaced with the foliated scrolls 8 8 and 9 9, abutting on the ornament 10 at the upper end of the oval back. Small floral ornaments are interspersed with the 35 stem and scroll ornamentation. The stem, scroll, and floral ornamentations are raised above the surfaces of the panels and the marginal surfaces of the brush-back.

To the eye the whole presents the appearance 40 of interlaced long floral stems curved to conform to the oval outline of the brush-back and the handle.

Having thus described my invention, what I claim as new, and desire to secure by Letters 45 Patent, is—

The design for the back of a brush or similar article substantially as herein shown and described.

In witness whereof I have hereunto set my 50 hand.

WILLIAM C. CODMAN.
